Primary Examiner — Sharon S Oum*Assistant Examiner* — Vanessa Martinez(57) **CLAIM**

The ornamental design for a solar wall light, as shown and described.

DESCRIPTION

FIG. 1 is a front, right and top perspective view of a solar wall light showing my new design;

FIG. 2 is a front, left and top perspective view thereof;

FIG. 3 is a rear, left and bottom perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines depict portions of the solar wall light and form no part of the claimed design.

1 Claim, 9 Drawing Sheets(56)
